UNITED STATES PATENT OFFICE.

JOHN M. DOLEN, OF WICONISCO, PENNSYLVANIA, ASSIGNOR TO HIMSELF,
WILLIAM H. THOMAS, AND JAMES J. KERWIN, OF SAME PLACE.

SAFETY-LAMP FOR MINERS' USE.

SPECIFICATION forming part of Letters Patent No. 257,670, dated May 9, 1882.

Application filed March 6, 1882. (No model.)

To all whom it may concern:

Be it known that I, JOHN M. DOLEN, of Wiconisco, in the county of Dauphin and State of Pennsylvania, have invented certain new and useful Improvements in Safety-Lamps for Miners' Use, of which the following is a full, clear, and exact description.

Reference is to be had to the accompanying drawings, forming part of this specification, in which similar letters of reference indicate corresponding parts in all the figures.

Figure 1 represents a side elevation of a safety-lamp for miners' use, constructed in accordance with the invention, and showing an extinguishing-case applied thereto when not extended. Fig. 2 is a vertical section, on the line *x x* in Fig. 1, of the same, showing the extinguishing-case as extended and operating to exclude or extinguish the light; and Fig. 3 is a transverse section thereof on the line *y y* in Fig. 2.

In safety-lamps for miners' use it is very important that effective means, capable of easy and rapid operation, should be provided for cutting off all communication between the flame inside of the lamp and the outside air or gases whenever danger exists from the lamp getting on fire.

One of the objects of this invention is to furnish such a means; and for this purpose the invention consists in a telescopic case arranged on the exterior of the wire gauze or cage of the lamp, which case also excludes dirt and is a protection against breakage.

This invention also consists in means for preventing the bowl or oil-receptacle of the lamp from becoming accidentally unscrewed, likewise in means for holding the burner to its place and for catching any escaping oil.

A represents the bowl or oil-receptacle of the lamp.

B is the base-piece of the main frame, into which the upper end of the bowl *A* is screwed.

B' is the top or upper ring of said frame, and *B²* *B²* are the rods which connect the base-piece *B* with the upper ring, *B'*, outside the wire gauze or cage of the lamp, and which form a portion of the main frame.

To prevent the bowl *A* from becoming accidentally unscrewed from the base-piece *B*,

which it is liable to do if not locked, and in doing which there is great danger when the lamp is in use in the mine, I provide these parts with a spring catch or bolt, *C*, which automatically engages with its keeper when the bowl *A* is in the position of being fully screwed home.

D is a hollow screw-cap arranged to fit a female thread in the upper part or neck, *c*, of the bowl *A*, and serving, by means of a perforated collar, *d*, on the burner *b*, and perforated washer or plate *d'* at the bottom of said cap, to hold the burner fast in the bowl, and to provide for the manipulation, as required, of the safety-wick trimming and raising wire *e*, which may be of the usual description. This hollow cap *D* prevents the oil from escaping and getting on the wire-gauze of the lamp and catches and holds any oil that may pass out of the bowl *A* otherwise than by the wick.

The wire gauze or cage *E* is represented as fitted with a double raised top, *E'*, which is also of wire-gauze, and virtually forms part of the cage. This raised double top rests, when in its place, upon a bent wire or frame, *f*, interposed between it and the top of the lower gauze.

F is a shield in the upper portion of the cage *E*, and secured by screw to the top thereof to protect said top from being rapidly burned out.

G *G'* *G²* *G³* are telescoping sections of an extinguishing-case arranged outside of the cage or gauze *E* *E'*, within the bars *B²* of the main frame, and fitted with a top, *G⁴*, which is mounted on or forms a cover for the section *G²*. These several tubular sections are made of sheet metal and have their longitudinal seams or joints closed by rivets, in preference to soldering them, to prevent them from coming apart by the heat to which they are exposed. The section *G³* is fitted to rest by a bar, *S*, upon the top of the supplementary gauze top *E'*, and the section *G²*, which is fitted to slide up and down over or outside of the section *G³*, has one or more openings, *g*, in its side, so that when the lower sections of the extinguishing-case are shut up within one another and the section *G²* is drawn outward in an upward direction, as shown in Fig. 1, the lamp is exposed for illuminating purposes, and a draft is established through the openings *g*. When, however, it

is required to extinguish the lamp, the same is done rapidly by extending the lower sections of the case in a downward direction and shutting down the section G^2 , as shown in Fig. 2, whereby the cage or wire-gauze of the lamp is wholly inclosed and the flame within it is extinguished. Said extinguisher or extinguishing-case not only serves to rapidly cut off all communication with the gas and other airs on the outside of the lamp and to quench the flame within the cage, but also to protect the cage or gauze from being broken when the lamp is being carried to and from the place of its use, and to keep it dry and clean when not in use.

Pivoted to the top of the main frame are one or more catches, h , which lock with or over the section G^3 of the case, and which, when turned to one side, out of engagement with the case, admit of the whole case being removed and the several sections of it being taken apart.

H is the cover of the lamp, provided with the usual ring or handle, i , for carrying the lamp. This cover is hinged on its one side to the top piece, B' , of the main frame, to provide for its being opened as usual and necessary. Said cover is fastened on its opening side by a hasp, k , and button or key l , which, on being suitably turned, locks the hasp, and which, when turned into a different position, unlocks the hasp and allows of the cover being opened. By

thus providing the cover with positive and rigid means for locking it the liability of said cover to be accidentally and suddenly opened, which endangers the breaking of the hinge of the cover and falling of the lamp, as now sometimes happens, and is attendant with great danger, is avoided.

Having thus fully described my invention, what I claim as new, and desire to secure by Letters Patent, is—

1. The telescoping tubular sections G G' , the section G^2 , provided with openings g , the section G^3 , having bar S , and the covering-section G^4 , in combination with the cage E E' and the frame-bars B^2 , as shown and described.

2. The combination, in a lantern, of a cage-body, E , wire-gauze E' , and supporting-frame f , as shown and described.

3. The externally-threaded cap D and the bowl having internally-threaded neck e , in combination with the burner b , having perforated collar d and washer-plate d' , whereby the burner may be made fast to the bowl, the trimming and raising wire may be readily manipulated, and the oil may be prevented from escaping on the cage or wire-gauze, as described.

JOHN M. DOLEN.
